WHEEL ACTUATED TREADLE FOR RAILWAY SIGNALING SYSTEMS

Andrew Brown, London, England, assignor to International Standard Electric Corporation, New York, N. Y.

Application September 26, 1936, Serial No. 102,707
In Great Britain October 28, 1935

6 Claims. (Cl. 246—246)

This invention relates to the arrangement of treadles to be operated by the wheels of a train in order that the number of wheels entering and leaving a given track section may be automatically counted for the purpose of controlling the signals.

It is necessary that treadles that cause the sending of impulses to the counting apparatus should be capable of rapid movement in order that contacts controlled thereby should be properly opened and closed for each wheel of a train travelling at high speed. If the treadles are light enough to respond correctly to wheels travelling at a high speed they may be operated accidentally by platelayers or others working on or traversing the track. On the other hand a treadle which requires so much force to depress it that it cannot be operated otherwise than by the passage of a wheel of a train may not count correctly the successive passage at high speed of a number of wheels.

Heavy treadles of various forms are already used in such a manner that on being depressed by the wheels of a train they operate contacts in an electric circuit although these treadles do not restore sufficiently quickly to control wheel counting contacts.

According to the present invention I arrange electrically in parallel with the wheel counting contacts, contacts operated by a heavy treadle placed in such position as to be depressed by the wheels of a train whenever the wheel counting contacts are being operated.

I prefer to arrange both the heavy treadle and the treadle operating the wheel counting contacts parallel with the track and to arrange a heavy treadle on the inside of one running rail and to counting treadle on the inside of the other running rail of the same track opposite the middle portion of the heavy treadle.

Both treadles may control normally made contacts connected in parallel in the electric circuit effecting the counting. When a train wheel is passing over the heavy treadle the contacts controlled thereby are open, and the opening and closing of the counting contacts are operative to control the counting circuits. It is not necessary that the heavy treadle should maintain its contacts open after it has been depressed by the first wheel of a train until the last wheel passes over it; it is only necessary that its contacts should remain open until after the re-closing of the counting contacts succeeding the passage of a wheel over the counting treadle. This will generally mean in practice that the heavy treadle

will maintain its contacts open during the passage of a group of wheels though its contacts may close before the first wheel of the next group of wheels re-opens it.

It is clear that with this arrangement operation of the wheel counting treadle when a train is not passing along the track will have no effect on the counting apparatus or on the signals, since the counting circuit will remain closed through the contacts of the heavy treadle.

The invention will be more fully explained in the following description taken in conjunction with the accompanying drawing.

The single figure of the drawing illustrates diagrammatically a signaling system embodying my invention.

Referring more particularly to the drawing reference numeral 1 indicates the normally made contacts which are adapted to be opened by passage of train wheels over the heavy treadle 2, and 3 indicates the normally made contacts which are adapted to be opened by simultaneous passage of train wheels over the light, counting treadle 4. The two sets of contacts are connected electrically in parallel to counting apparatus 5 by means of wires 6, 7 and 8, 9.

The apparatus is located between rails 10 and 11, shown in broken cross section. Projections 12 and 13 on treadles 2 and 4, respectively, raise the operating base of these treadles into position to enable the wheels of passing trains to operate both treadles and open contacts 1 and 3.

What is claimed is:

1. An arrangement of treadles in a track way for operating an electric circuit to count the wheels of a train passing thereover, comprising two contacts connected in parallel in said circuit, a counting treadle arranged in said track way and adapted to be depressed and released for each wheel passing thereover for operating one of said contacts, and a slow acting treadle arranged in said track way and adapted to be depressed by the passage of a wheel thereover for operating the other contact, said slow acting treadle being so arranged relative to said counting treadle as to be depressed whenever the counting treadle is being operated.

2. An arrangement as claimed in claim 1 in which both treadles are arranged parallel to adjacent running rails of the same track.

3. An arrangement as claimed in claim 1 in which the contacts controlled by both treadles are normally closed and are opened when a wheel passes over the corresponding treadle.

4. An arrangement of treadles for operating

- an electric circuit for counting the wheels of a vehicle passing along a fixed course comprising a counting means connected to said circuit, a counting contact and another contact in said circuit, said contacts being connected in parallel with respect to said counting means, a counting treadle for controlling one of said contacts arranged in said course and adapted to be depressed and released for each wheel passing 5
- thereover, and a slow return treadle arranged in said course for controlling said other contact, said slow return treadle being so arranged in the course of the vehicle as to be depressed whenever said counting treadle is being operated.
- 10 5. An arrangement as claimed in claim 4, in which the contacts controlled by both treadles are normally closed and are arranged to be opened by passage of a wheel over the corresponding treadle.

6. An arrangement of treadles for operating an electric circuit to count the wheels of a train passing over a given track section, comprising a counting treadle arranged relative to said track in the course of said train for depression and release by each wheel passing thereover, counting contacts controlled by said counting treadle, a slow return treadle arranged relative to said track section in the course of said train and positioned relative to said counting treadle so as to be simultaneously depressed therewith upon passage of each said wheel, and contacts connected in parallel with said counting contacts controlled by said slow return treadle, whereby said last named contacts will be open whenever said counting 10 contacts are operated by a train.

ANDREW BROWN.
